CLOTHESLINE SUPPORT

Filed May 10, 1927

H.M. Snoddy

By Watson E. Coleman
Attorney

UNITED STATES PATENT OFFICE.

HARVEY M. SNODDY, OF MILLER, SOUTH DAKOTA.

CLOTHESLINE SUPPORT.

Application filed May 10, 1927. Serial No. 190,263.

This invention relates to a clothes-line support and it is an object of the invention to provide a device of this kind including a member adjustable in a vertical direction and with which a clothes-line is adapted to be engaged, the adjustment of the member permitting the line to be lowered to facilitate the application or removal of articles with respect to the line.

Another object of the invention is to provide a device of this kind including a vertically disposed post having an arm pivotally engaged with the upper portion thereof for movement in a vertical direction together with means for holding said arm in either raised or lowered position, said arm being adapted to have a clothes-line engaged therewith.

The invention consists in the details of construction and in the combination and arrangement of the several parts of my improved clothes-line support whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawing, wherein:

Figure 1 is an elevational view of a clothes-line support constructed in accordance with an embodiment of my invention;

Figure 2 is a view partly in top plan and partly in section of the structure as illustrated in Figure 1;

Figure 3 is a sectional view taken substantially on the line 3—3 of Figure 1;

Figure 4 is a sectional view taken substantially on the line 4—4 of Figure 1.

As disclosed in the accompanying drawing, P denotes a vertically disposed post of desired dimensions and which has secured to a face thereof by the bolts 1 a plate 2. The lower portion of this plate 2 is provided with an outstanding flange 3 through which is slidably disposed a locking bolt 4. This bolt 4 above the flange 3 is provided with a collar 5 which, by contact from above with the flange 3, serves to limit the downward movement of the bolt. The bolt is constantly urged downwardly by a spring 6 encircling the upper portion of the locking

bolt and interposed between the collar 5 and a pivot member or bolt 7 disposed through the upper portion of the post P and the plate 2 and projecting outwardly beyond the post 60 for a purpose to be hereinafter referred to.

The extended portion of the pivot member or bolt 7 is disposed through an elongated arm A at substantially the longitudinal center thereof whereby said arm A is supported 65 for swinging movement in a vertical direction. As herein set forth, this arm A is of a channel type with its longitudinal marginal flanges 8 disposed toward the post P. At its central part the arm A is provided with 70 a depending plate 9 herein disclosed as semi-circular in form with its curved periphery defined by an inwardly disposed flange 10 provided with spaced notches or recesses 11. The notches or recesses 11 are herein shown 75 as three in number and when the locking bolt 4 is engaged with the intermediate notch or recess, the arm A is effectively held in a horizontal position and upon lowering either of the extremities of the arm A, such arm is held in such lowered position by engagement 80 of the bolt 4 within one of the outer notches or recesses 11.

Suitably secured to the collar 5 and extending along the arm A in opposite directions are the flexible members 12 the same being disposed over suitable guide members 14. Each of these members 12 is disposed through an end plate 15 carried by each extremity of the arm A and depending below 90 the arm a distance to bring the same within the ready reach of a person standing on the ground. Upon pull being given to either of the flexible members 12 the locking bolt 4 will be pulled upwardly against the tension 95 of the spring 6 and freed from locking engagement with the flange 10 of the plate 9 and an end portion of the arm swung downwardly, the locking bolt 4 upon release of pull thereon engaging an outer notch or recess 11 to hold the arm A in such tilted or inclined position. The arm A is returned to its horizontal position in the same way although pull be preferably imposed upon the flexible member 12 depending from the 100 elevated or raised end of the arm A.

Each end portion of the arm A is provided with an opening 16 through which a clothes-line C is adapted to be directed, said line being also threaded through an opening 17 110 provided in a vertically disposed shaft 18 rotatably supported by the flanges 8 of the

arm A, said shaft 18 extending below the arm and being provided with a cross bar 19 whereby the same may be readily and conveniently rotated. Fixed to the shaft 18 closely adjacent to one of the flanges 8 is a ratchet wheel 20 with which engages a pawl or dog 21 pivotally engaged with such flange.

When it is desired to tighten the clothes-line C the same may be readily accomplished by rotating the shaft 18 winding the line therearound, retrograde rotation of the shaft being prevented by the coacting ratchet wheel 20 and pawl 21.

With a clothes-line support constructed in accordance with an embodiment of my invention the line C may be normally held at a considerable height above the ground, thus assuring the articles suspended therewith to entirely clear the ground.

From the foregoing description it is thought to be obvious that a clothes-line support constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. A clothes line support comprising a post, an arm pivotally engaged with the upper portion of the post, the arm being channel-shaped in cross section at the middle, locking means holding the arm in any one of a plurality of angular relations to the post, the channel forming a housing for the locking means, and a flexible member attached to the locking means for the release thereof extending longitudinally along the arm and depending from the opposite ends thereof.

2. A clothes line support comprising a post, an arm pivotally engaged with the upper portion of the post, the arm being channel-shaped in cross section at the middle, the middle portion of the channel being enlarged in concentric relation to the pivot, locking means holding the arm in any one of a plurality of angular relations to the post, the locking means comprising a spring actuated bolt, guides on the post and pivot for the bolt, the flange on the enlarged portion of the arm having notches for engagement with the bolt, the enlarged portion of the channel forming a housing for the locking means, and a flexible member attached to the bolt for the release thereof, extending longitudinally along the arm and depending from the opposite ends thereof.

In testimony whereof I hereunto affix my signature.

HARVEY M. SNODDY.
